[57] CLAIM

The ornamental design for a fireman's rope bag, as shown and described.

DESCRIPTION

FIG. 1 is a front elevational view of a fireman's rope bag showing my new design;

FIG. 2 is a rear elevational view thereof;

FIG. 3 is a top plan view thereof;

FIG. 4 is a bottom plan view thereof;

FIG. 5 is a side elevational view thereof, the opposite side being a mirror image; and,

FIG. 6 is a bottom plan view thereof, with the side flaps for the lower rope compartment fully detached from the hook and loop fastener.

The window-like strip on the front of the upper, rappelling-rope compartment closure lid is not a window but represents a reflector strip.

The broken lines in FIGS. 1–4 represent a carrying strap, not a part of the design.
